(57) **CLAIM**

The ornamental design for a massage chair, as shown and described.

DESCRIPTION

FIG. 1 is a front view of a massage chair of the present invention.

FIG. 2 is a rear view of the massage chair of FIG. 1.

FIG. 3 is a top view of the massage chair of FIG. 1.

FIG. 4 is a bottom view of the massage chair of FIG. 1. FIG. 5 is a left side view of the massage chair of FIG. 1. The right side is a mirror image of the left side.

FIG. 6 is a front view of the massage chair of FIG. 1, shown with air bags inflated.

FIG. 7 is a rear view of the massage chair of FIG. 1, shown with air bags inflated.

FIG. 8 is a top view of the massage chair of FIG. 1, shown with air bags inflated.

FIG. 9 is a bottom view of the massage chair of FIG. 1, shown with air bags inflated.

FIG. 10 is a left side view of the massage chair of FIG. 1, shown with air bags inflated. The right side view with the air bags inflated is a mirror image of the left side view with the air bags inflated.

FIG. 11 is a left side view of the massage chair of FIG. 1, shown with a backrest portion reclined and a footrest portion raised.

FIG. 12 is a top view of the massage chair of FIG. 1, shown with speaker portions turned inward.

FIG. 13 is a left side view of the massage chair of FIG. 1, shown with a headrest portion raised.

FIG. 14 is a front view of a detachable left armrest portion of the massage chair of FIG. 1. The detachable right armrest portion of the massage chair is symmetrical to the detachable left armrest portion.

FIG. 15 is a rear view of the detachable left armrest portion of the massage chair of FIG. 1.

FIG. 16 is a top view of the detachable left armrest portion of the massage chair of FIG. 1.

FIG. 17 is a bottom view of the detachable left armrest portion of the massage chair of FIG. 1.

FIG. 18 is a left side view of the detachable left armrest portion of the massage chair of FIG. 1.

FIG. 19 is a right side view of the detachable left armrest portion of the massage chair of FIG. 1.

FIG. 20 is a perspective view of the massage chair of FIG. 1, shown with detachable right and left armrest portions removed; and,

FIG. 21 is a perspective view of the massage chair of FIG. 1.

The armrests in FIGS. 14-19 are shown separately for easy of illustration.
